UNITED STATES PATENT OFFICE.

EMIL A. SAUBER, OF PHILADELPHIA, PENNSYLVANIA, ASSIGNOR TO
HAGEDORN & MERZ, OF SAME PLACE.

BOSOM-PLAITING ATTACHMENT FOR SEWING-MACHINES.

SPECIFICATION forming part of Letters Patent No. 449,885, dated March 31, 1891.

Application filed November 22, 1890. Serial No. 372,302. (No model.)

To all whom it may concern:

Be it known that I, EMIL A. SAUBER, a citizen of the United States of America, residing at Philadelphia, in the county of Philadelphia and State of Pennsylvania, have invented certain new and useful Improvements in Bosom-Plaiting Attachments for Sewing-Machines, of which the following is a specification, reference being had therein to the accompanying drawings.

My invention has relation to sewing-machine attachments, is designed and adapted particularly for use in the manufacture of shirts, and has for its object the provision of novel, simple, and efficient means whereby the central plait of the bosom of a garment of the above-mentioned class may at a single operation be automatically formed and the formation of the double row of stitching 20 therein adjacent to its edges be simultaneously accomplished.

Heretofore in the formation of a plait of the above character, preparatory to the stitching thereof and subsequently to the cutting 25 of the bosom to the proper shape, six distinct operations have been necessary, viz: the formation of the entrant or bellows fold composing one side of the plait, the formation of a like fold for the other side of the plait, the 30 formation of each fold involving two opposite bends of the fabric, and the stitching, separately, of each side of the plait for rendering permanent said folds.

My invention consists in the details of construction and in the combinations of parts, as hereinafter fully described and claimed, and as shown clearly in the accompanying drawings, wherein—

Figure 1 is a plan view of my improvements in position on the cloth-plate and table of a sewing-machine. Fig. 2 is a side elevation of that portion of said improvement which rests on the cloth-plate aforesaid, as in the above figure. Fig. 3 is a similar view of 45 the portion of my improvements which rests on the sewing-machine table, as in Fig. 1; and Fig. 4 is a perspective view of a section of a shirt-bosom, showing the central plait as formed by the improvements aforementioned.

Having reference to the employment of the spreader A, which is sustained on the upward

extension or block a of the arm A', which latter is hinged on the pin b in the ears or lugs b' of the base-plate B, said base-plate being secured to the cloth-plate C of the machine, 55 preferably by the screw b², in such position as to bring said spreader in the line of feed and directly in front of the needles c c', secured in the holder c² on the end of the needle-bar c³, such needle-bar, as usual, reciprocating within the box C' therefor on the arm of said machine. The arm A' is maintained in its normal position, which is as shown in full lines in Figs. 1 and 2, by the spiral spring b³ encircling said pin and having its ends secured to said arm and base-plate, respectively, the latter and the arm constituting in effect the leaves of a spring-hinge.

D is a spring-metal arm pivotally sustained at its inner end on the block d through the 70 medium of the screw d' and the washer d² and adapted to swing radially thereon, the outer free end of said arm being enlarged laterally, forming the head d³, the edge of which tapers inwardly toward the line of feed, and 75 the height of the block d is such that when the arm D is swung into the position shown by the dotted lines in Fig. 1, where it is limited in its movement by the pin d⁴ on said block and where its head rests beneath the 8c wedge-shaped spreader A, the tendency of the head d³ will be upward toward the under side of said spreader.

E is another spring-metal arm, hook-like in side elevation, having its free end formed into 85 a head e, like the head d³, permanently occupying a like position on the other side of the line of feed in the same horizontal plane, having the same upward tendency due to the spring of the arm, but having its edge extending in the opposite direction, so that the intermediate space diminishes in width inwardly, while the width of the spreader A, under which the heads rest, diminishes outwardly. The other end e' of this arm is 90 widened at one side, as at e², so as to insure a broad bearing on the under side of the bed-plate C, to which it is rigidly secured by the screws e³. The spreader A and the arms D and E constitute the plait-former.

F' are oppositely-disposed guides having therein longitudinal slots f f' and adjustably

secured on the base-plate G, which is secured by the screws g to the sewing-machine table H through the medium of the set-screws $g' g^2$, the free ends $f^2 f^3$ of such guides being bent 5 on lines parallel with the edges of the heads e and d^3 and extending, hook-like, parallel with the main portions thereof, the distance apart of the guides being governed by the width of the bosom to be plaited, their proper 10 positions being at equal distances from the center of the line of feed.

The operation is as follows: The arm D is 15 swung into the position shown by the full lines in Fig. 1 and the arm A' swung into the position shown by the dotted lines in Fig. 2. Then the bosom-blank is placed with one of its edges within the guide F and under the upper free end of the arm E and then given a turn around the head e, causing it to lie on 20 said end, forming the entrant-fold k in the bosom I. The arm A' is swung back into the position shown in full lines in Figs. 1 and 2. The bosom is then given another turn oppositely to the last turn and laid on the spreader 25 A, forming the plait K, and then allowed to drop below the edge of said spreader, whereupon the arm D is swung back into the position shown by the dotted lines in Fig. 1 and the full lines in Fig. 2, forcing the afore- 30 said dropped portion of the bosom beneath the edge of the spreader A, forming the entrant-fold k', in which position the remainder of the bosom will rest beneath the arm D and will be placed in the guide F' also. 35 The plait K will be exactly in the middle, as shown by the broken line x in Fig. 2, because of allowance having been made for the formation of said plait, and the guides F F' adjusted accordingly. Finally, the bosom, 40 in the condition above described, is placed under the presser-foot L, which is widened so as to accommodate it to the width of the line of feed and to the width of the feed M, which latter is also widened correspondingly to the 45 distance apart of the needles c c', and the machine started, the inclines of the guides F F' facilitating the feeding of the bosom-blank, under draft of the feed mechanism, to the folding devices, and the flaring of the heads 50 d^3 and e, under such draft, facilitating the folding operation, the innermost edges or ends of said heads being just within the axial lines of the needles, insuring the passage of the latter through the inner edges of the entrant-folds 55 and the simultaneous stitching on the lines $c^2 c^3$ of both to the plait K, while the block a

prevents such edges from getting away from this position by being interposed between them, and the spreader a spreads the plait to the desired width, the above operations continuing without further assistance until the bosom is plaited and stitched. 60

What I claim as my invention is as follows:

1. In a plaiting attachment for sewing-machines, the combination, with the cloth-plate, of a stationary and a horizontally-swinging arm, with their free ends normally opposite in the same horizontal plane and in the line of feed, the facing edges of said ends converging toward the needles, and a spreader 70 projecting over said edges, substantially as and for the purpose specified.

2. In a plaiting attachment for sewing-machines, the combination, with the cloth-plate, of a stationary and a horizontally-swinging 75 arm, with their free ends normally opposite in the same horizontal plane and in the line of feed, said free ends being widened laterally and their facing edges converging toward the needles, and a T-shaped spreader with its 80 shank interposed between and its head projecting over said edges, substantially as and for the purpose specified.

3. In a plaiting attachment for sewing-machines, the combination, with the cloth-plate, 85 of a stationary and a horizontally-swinging arm, with their free ends normally opposite in the same horizontal plane and in the line of feed, said free ends being widened laterally and their facing edges converging toward the 90 needles, and a vertically-swinging spring-controlled arm, with a T-shaped spreader thereon, with its shank interposed between and its head projecting over said edges, substantially 95 as and for the purpose specified.

4. In a plaiting attachment for sewing-machines, the combination, with the cloth-plate, of a stationary and a horizontally-swinging arm, with their free ends normally opposite in the same horizontal plane and in the line 100 of feed, the facing edges of said ends converging toward the needles, a spreader projecting over said edges, and a guide for the fabric in front of said arms and spreader, substantially as and for the purpose specified. 105

In testimony whereof I affix my signature in presence of two witnesses.

EMIL A. SAUBER.
